McBean & Co., Los Angeles, Calif., a corporation of California

Application August 27, 1953, Serial No. 26,604

Term of patent 14 years

(Cl. D44—15)

To all whom it may concern:

Be it known that I, George T. James, a citizen of the United States, residing at Pasadena, county of Los Angeles, and State of California, have invented a new, original, and ornamental Design for a Plate or the like, of which the following is a specification, reference being had to the accompanying drawing, forming part thereof.

Fig. 1 is a top plan view of a plate or the like showing my new design.

Fig. 2 is a side view thereof.

Figs. 3 and 4 are enlarged sections taken through different portions of a rim of the plate illustrated in Fig. 1, the sections being taken along planes III—III and IV—IV, respectively.

I claim:

The ornamental design for a plate or the like, substantially as shown.
